UNITED STATES PATENT OFFICE.

HAROLD B. CRANSHAW, OF NEWTON, MASSACHUSETTS, ASSIGNOR TO BURNITOL MANUFACTURING COMPANY, OF EVERETT, MASSACHUSETTS, A CORPORATION OF MAINE.

RECEPTACLE.

Application filed September 17, 1928. Serial No. 306,443.

This invention relates to receptacles and pertains more particularly to paper receptacles designed for use as sputum flasks or for similar purposes. The principal object 5 of the invention is to provide a receptacle of this character which may be cheaply manufactured and readily assembled from a single sheet of material, which has improved means for interlocking the side portions, thereby 10 effectively to prevent collapse or casual separation of its interconnected portions, and which is equipped with a close fitting cover portion and a pocket adapted to receive and frictionally retain the cover. Other objects 15 reside in the particular construction of the sputum flask hereinafter described and defined in the appended claims, the novel features of which are in the nature of improvements upon the article described in the 20 patent to Sheline No. 1,274,613 dated August 6, 1918.

A preferred embodiment of the invention is illustrated in the accompanying drawings, in which:

Fig. 1 is a plan view of a blank from which the receptacle is constructed;

Fig. 2 is an end view of the completely assembled receptacle in closed position;

Fig. 3 is a similar view in opened position;

Fig. 4 is a plan view of the receptacle shown in Fig. 2 with the top portion folded inwardly;

Fig. 5 is a section through the receptacle taken on the line 5—5 of Fig. 2, illustrating particularly the interlocking connection between the side portions thereof;

Fig. 6 is a fragmentary plan view, partly in section along said line, showing an initial stage of the folding operation performed 40 upon the blank of Fig. 1; and

Figs. 7 to 10 are similar views illustrating progressive stages in the folding operation.

The improved receptacle may be formed of heavy paper, cardboard or other suitable 45 imperforate sheet material of appropriate stiffness, and is preferably formed from a single sheet of material stamped or otherwise cut in the shape shown in Fig. 1, and provided with scored or otherwise weakened

lines separating its various portions and furnishing guides upon which said portions are folded to produce the receptacle.

The blank comprises a back portion 11, a front portion 12, an intermediate bottom portion 13 and a top or cover portion 14 disposed at the outer end of the back portion, said portions being arrayed in line, centrally of the blank; similar lateral portions 15 and 16 adapted to be folded along the back portion 11, and other similar lateral 55 portions 17 and 18 adapted to be folded along the front portion 12; side portions 19 which fold upon the ends of the bottom 13 and from the sides or ends of the assembled receptacle; similar lateral web portions 20 60 and 21 connecting the portion 18 to the portion 19, respectively; substantially similar tab portions 22 preferably formed as integral extensions of the lateral portions 16 and 18 respectively in opposite sides of the blank; 65 and substantially similar flap extensions comprising portions 23 and 24 preferably formed on the lateral portions 15 and 17 respectively at opposite ends of the blank, whereby to provide a blank having substantially symmetrical sides.

The lines of fold which form visible folded edges between the lateral portions of the assembled receptacle are indicated by the numerals 25, 26 and 27; the fold lines 80 of the tabs 22 are denoted by the numeral 28, those of the flap portions 23 by the numeral 29, and those of the flap tongues 24 by the numeral 30; and the top portion 14 may have a pair of parallel fold lines as 85 shown at 31 and 32. The side portions 19 are preferably triangular in shape and the web portions 20 and 20 are adapted to fold upon the lines 33 in the manner of a bellows and the lateral portions 15, 16 and 17, 18 90 may fold in a similar manner on diagonal lines 34 and 35 respectively, so that the forward portions of the receptacle may be pressed rearwardly against the slanting edges of the said side portion, as indicated 95 in Fig. 2, to provide a compact assemblage.

After the blank has been formed substantially as above described, it may be folded

together and its lateral portions are preferably interlocked in the following manner, as illustrated in Figs. 6 to 10. The right-hand lateral portion 15 is folded inwardly 5 along the inside of the back portion 11 and the adjoining portion 16 is folded outwardly at line 34 against the face of the portion 15 (Fig. 6), and the left-hand portions 15 and 16 are then folded over said right-hand portion 10 in a similar manner (Fig. 7). At this stage the flap extension 23—24 lies against the inside of the cover 14, and the tab 22 is superposed upon the flap extension. Tab 22 is then folded rearwardly on line 28 over 15 the upper edge of right-hand portion 16 so that it lies between the outer faces of the right-hand folded portions 15 and 16 (Fig. 8). Next the flap extension 23, 24 is folded forwardly on line 29 over the folded edge of 20 tab 22 (Fig. 9), and finally the segment 24 of the flap extension is folded rearwardly and upwardly on line 30 behind the folded edge 34 of the left-hand portions 15 and 16 (Figs. 5 and 10). The respective right and left-hand lateral portions 15 and 16 are thus effectively interlocked and can not become accidentally separated or pulled apart, as would be possible if the tab 22 were not provided.

30 The forward lateral portions 17 and 18 are folded along the inside of the front 12 and are interlocked in substantially the same manner to complete the assemblage which, before closing, appears as shown in Figs. 35 3 and 4. It will be noted from these illustrations that the folding and interlocking operations just described furnish a pocket 36 between the front 12 and said interlocked portions 17 and 18. When the receptacle is 40 closed (Fig. 2) the cover 14 is folded upon lines 31 and 32 and its tongue is pushed downwardly into this pocket and is frictionally retained therewithin, to provide a substantially non-spillable container. After 45 opening the top or cover 14, the receptacle may readily be extended by virtue of the bellows web or end portions 2 and 21 which are not interlocked.

A receptacle having the improved feature 50 above described and pointed out in the appended claims is inexpensive and easy to manufacture and assemble, convenient in use and readily carried in the pocket; its parts are tightly locked together and the 55 cover may be quickly secured over the mouth of the closed container to enclose and retain its contents. The sheet material from which the receptacle is formed may be waterproofed by any appropriate treatment to 60 render the receptacle impervious. It will be understood, however, that the details of structure herein illustrated may be modified as desired to suit particular purposes without departing from the spirit of this invention, as defined in the following claims.

I claim:

1. A receptacle comprising a central wall portion, two lateral folded wall portions connected to opposite sides of the central portion and folded along the said central portion a tab on one of said lateral portions folded over the second lateral portion, and a flap on said second portion folded over and then under the first lateral portion thereby to interlock said portion. 70

2. A receptacle comprising a central wall portion, two lateral wall portions connected to opposite sides of the central portion, the lateral portions being folded inwardly along said opposite sides and then outwardly on 80 axes oblique to each other, a tab on one of said lateral portions folded between the folded portions of the second lateral portion, and a flap on the other of said lateral portions folded over the first lateral portion 85 and under the oblique axis of said first portion thereby to interlock said portions.

3. A receptacle comprising a substantially rectangular back portion, two lateral portions connected to opposite sides of the back 90 portion, each of said lateral portions consisting of two integral substantially triangular portions folded about axes oblique to said opposite sides respectively, a tab on the upper edge of the forward triangular portion of one of said lateral portions folded over the upper edge of the nearest triangular portion of the other lateral portion, and a flap on the upper edge of the rear triangular portion of the second-named lateral 100 portion folded over the tab fold and around the oblique axis of the first-named lateral portion so as to lock said portions together. 105

4. A receptacle comprising a substantially rectangular back portion, two lateral portions connected to opposite sides of the back portion, each of said lateral portions consisting of two integral substantially triangular portions folded about axes oblique to 110 said opposite sides respectively, a tab on the upper edge of the forward triangular portion of one of said lateral portions folded over the upper edge of the nearest triangular portion of the other lateral portion, and a flap on the upper edge of the rearward triangular portion of the second-named lateral portion folded over the tab fold and around the oblique axis of the first-named lateral portion so as to lock said portions together, 115 a front portion, other lateral portions connected to opposite sides of the front portion and similarly interlocked, and a top portion connected to the upper edge of the back portion and adapted to fit between the front portion and its interconnected lateral portions. 120

5. A receptacle comprising a back portion having a top portion connected at its upper edge, a front portion, two lateral portions connected to opposite sides of the front por- 130

tion, the lateral portions being folded inwardly and along said front portion and then outwardly on axes oblique to each other, a tab on one of said lateral portions folded 5 over the second lateral portion, and a flap on the second lateral portion folded over the first lateral portion and under the oblique

axis of said first portion, thereby to interlock said lateral portions and to provide a pocket between the front portion and the interlocked portion to receive said top portion. 10

Signed by me at Boston, Massachusetts, this 11th day of September, 1928.

HAROLD B. CRANSHAW.
